UNITED STATES PATENT OFFICE.

ELIS TÖRÖK, OF NEW YORK, N. Y.

DIRIGIBLE AIRSHIP.

1,115,457.

Specification of Letters Patent. Patented Oct. 27, 1914.

Application filed June 4, 1914. Serial No. 842,934.

To all whom it may concern:

Be it known that I, ELIS TÖRÖK, a subject of the King of Hungary, residing at New York, in the county of New York and State 5 of New York, have invented certain new and useful Improvements in Dirigible Airships, of which the following is a specification.

This invention relates to certain new and useful improvements in dirigible air ships.

10 An object of the present invention is to provide a dirigible air ship in which the gas bag is made in the usual shape, but is formed of thin metal, such as aluminum and filled with gas.

15 A further object of the present invention is to provide a dirigible air ship in which the gas bag is rotatable and formed of thin metal divided into a plurality of independent gas compartments so that the entire 20 bag will not be incapacitated should damage result to a single compartment.

25 A further object of the invention is to provide a car of an air ship, built in accordance with this invention, with doors in the bottom thereof so that the device may be used in time of war for dropping bombs, and with novel means for regulating the descent of the ship.

With the above general objects in view 30 and others that will appear as the nature of the invention is better understood, the same consists in the novel construction, combination and arrangement of parts to be herein-after more fully described and then claimed.

35 In the accompanying drawings which illustrate the preferred embodiment of my invention and to which reference is had herein by like characters designating corresponding parts throughout the several 40 views:—Figure 1 is a side elevational view of the air ship. Fig. 2 is a cross vertical view of the same. Fig. 3 is a side elevational view partly in section of a portion of the device illustrating the manner of connecting 45 the gas bag sections. Fig. 4 is a top plan view of a portion of the car with the bag removed. Fig. 5 is a detail sectional view of the end gas bag. Fig. 6 is a detail sectional view of one of the compartment joints illustrating the manner in which the suspending 50 cables pass thereover. Fig. 7 is a perspective view of a portion of the mechanism for operating the wings, and Fig. 8 is a sectional view of one of the wings attached to the side 55 of the car.

Briefly described, the invention consists in

employing a gas bag formed of thin metal, such as aluminum and which bag is divided into a plurality of independent gas compartments so that if injury results to a single 60 compartment the whole device will not be rendered inoperative. The present invention also employs a car suspended beneath the gas bag, which car has pivoted to each side thereof of a wing operated by mechanism extending 65 within the car to decrease the velocity of descent should the device become injured in any manner, or in the usual descent of the same.

Referring more in detail to the accompanying drawings, the reference numeral 10 designates the gas bag formed of a plurality of independent gas sections 11. This gas bag is preferably formed of thin metal such as aluminum or other metal light in weight, 75 the sections 11 being suitably joined together as by riveting, as clearly shown in Fig. 6. The opposed outer edges of the adjacent sections are bent to form recesses 12 having journaled therein at suitably spaced intervals a plurality of sheaves 13. These sheaves 13 are journaled in the recesses 12 formed between each of the adjacent sections as clearly shown in Fig. 3 and have passed thereover cables 14 for suspending the car 85 designated in general 15. The gas bag 10 tapers from its center toward each end as shown in Fig. 1 and is rotatably mounted on the longitudinal shaft 16, the shaft 16 carrying on each end thereof exteriorly of 90 the bag 10 the sheave 17 which has a chain connection 18 with the car 15.

The car 15 consists of a boat-like structure provided with a plurality of helicopter propellers 19 and an end driving propeller 20, such propellers being driven by the motors 21 through the gear connections 22, the end propeller 20 having the chain connection 22' with the motor shaft 23 of one of the motors 21. As shown in Figs. 1 and 4 100 the rudder 24 is preferably located at the front end of the car and is pivoted thereto as at 25, the rudder having a rope connection 26 passing over sheaves 27 to the steering wheel 28. The bottom of the car 15 is 105 provided with a plurality of openings 29 closed by the doors 30, such openings constituting a bottom sight and through which bombs may be dropped.

Pivoted to each side of the car 10 on the 110 rod 31 is a side wing 32 that extends substantially the entire length of the car 15

and normally assumes its position adjacent the car as shown in Fig. 2. Means are provided to cause the wings 32 to assume a horizontal position as shown by dotted lines 5 in Fig. 2 and consists in journaling a rock-shaft 33 exteriorly of the car and mounting on said shaft a plurality of wing engaging arms 34. Hand levers 36 are carried by the shaft 33, and extend into the car 15, 10 through the openings 35 provided in the sides. When the levers 36 are operated, the arms 34 engage the wings 32, to cause the same to assume the horizontal position shown in dotted lines in Fig. 2.

15 The suspending ropes 14 pass through eyes 37 carried by the upper edge of the car and continue downwardly as at 14' to be secured in any suitable manner as at 38 to the bottom of the car.

20 In operation, the compartments of the gas bag 10 are filled with enough gas to elevate the car 15 from the ground, after which the propellers 19 and 20 are operated to cause the device to be both elevated and driven in 25 a forward direction. The gas bag 10 by having the rope and sheave connection 13 and 14 with the car 15 may have free rotary movement on the shaft 16 relative to the said car, and should one of the compartments 30 11 of the bag 10 become broken, punctured or otherwise injured, the bag 10 may be rotated to move the injured part to a point adjacent the car 15 so that the same may be repaired. It will be noted that by 35 forming the gas bag of a plurality of sections that the whole bag is not rendered inoperative should one of the sections become broken or otherwise injured.

The device may be steered by the rudder 40 26 which is controlled by the steering shaft 28 as shown in Fig. 4 while the door openings 29 are provided for the purposes above stated.

Should it be desired to decrease the veloc-

ity of descent of the air ship, the levers 36 45 are moved to cause the arm 34 to move to horizontal position, the side wings 32 as shown in Fig. 2 offering resistance to the descending movement of the device.

While the drawings show the preferred 50 embodiment of my invention, I do not wish to confine myself to the exact details of construction shown, as various forms, modifications and arrangements of the parts as shown may be had without departing from 55 the spirit and scope of the invention as claimed.

What I claim as new is:—

1. In a dirigible air ship, a gas tank formed of a plurality of independent sections made gas tight and joined together, an annular groove at each joint, sheaves revolvably mounted in the grooves, cables passing over said sheaves, a car suspended by the cables and propellers carried by the car. 60
2. In a dirigible air ship, a gas tank, a car suspended therefrom, propellers carried by the car, a wing pivoted to each side of the car and extending substantially the entire length thereof, and means for operating 70 said wings, comprising pivotally-supported arms, a rock shaft, and a lever for turning said shaft, said lever extending within the car.
3. In a dirigible air ship, a gas tank 75 formed of thin metal and divided into a plurality of independent gas compartments, formed with annular grooves at the joints of the sections, and means within said grooves for effecting the rotation of the 80 tank.

In testimony whereof I affix my signature in presence of two witnesses.

ELIS TÖRÖK.
